US00D529295S

(12) United States Design Patent (10) Patent No.: US D529,295 S
(45) Date of Patent: * Oct. 3, 2006

(54) NONWOVEN PRODUCT HAVING
PATTERNED INDICIA

(75) Inventors: Bernhardt E. Kressner, Appleton, WI (US); Timothy M. McFarland, Neenah, WI (US); Pamela M. Thompson, Neenah, WI (US); Wendy Jahner, Olatha, KS (US)

(73) Assignee: Kimberly-Clark Worldwide, Inc., Neenah, WI (US)

() Term: 14 Years

(21) Appl. No.: 29/255,104

(22) Filed: Mar. 3, 2006

Related U.S. Application Data

(62) Division of application No. 29/233,333, filed on Jun. 30, 2005, now Pat. No. Des. 518,647, which is a continuation of application No. 10/325,469, filed on Dec. 19, 2002.
